UNITED STATES PATENT OFFICE.

PHILEAS T. CHAPLEAU, OF CHICAGO, ILLINOIS, ASSIGNOR TO AMERICAN CUTLERY COMPANY, OF CHICAGO, ILLINOIS, A CORPORATION OF ILLINOIS.

GUARD FOR PUNCH-PRESSES.

1,153,603.

Specification of Letters Patent. Patented Sept. 14, 1915.

Application filed January 15, 1915. Serial No. 2,370.

To all whom it may concern:

Be it known that I, PHILEAS T. CHAPLEAU, a citizen of the United States, residing at 3520 South Rockwell street, Chicago, in the county of Cook and State of Illinois, have invented a new and useful Improvement in Guards for Punch-Presses, of which the following is a specification.

My invention relates to guards for punch-
10 presses, of the variety involving a hingedly supported member adapted to be swung automatically from a position in which it does not obstruct the workman in positioning the work to be operated on by the punch-press
15 when the plunger of the press is in raised position, to a position in which the hands of the operator, should they remain in a dangerous position while the plunger is descending, will be forced out of the path of
20 the punch; my object being to provide a novel, simple and inexpensive form of guard of this general character which may be readily adjusted to machines of different sizes as well as to plungers of different sizes and
25 presenting different lengths of stroke.

Referring to the accompanying drawings, Figure 1 is a view in side elevation of a portion of a punch-press of common form equipped with a guard constructed in accordance with my invention, the guard being shown in the position it occupies when the plunger is uppermost. Fig. 2 is a similar view showing the position occupied by the guard when the plunger has moved to its lowermost position. Fig. 3 is a view in front elevation of the punch-press of Fig. 1; and Fig. 4, a perspective view of the guard-proper removed from the machine, a portion thereof being shown in section.

As the punch-press illustrated is one of common form, a brief description thereof only will suffice. The frame of the punch-
40 press is represented at 5, it being equipped with guides 6 in which the plunger 7 carrying the male die elements or punch 8, is confined to be reciprocated up and down by mechanism, not shown, the punch 8 co-operating with the die block 9 located below them and upon which the work to be operated on would be positioned.

The guard-proper of my improved construction is represented at 10, it being of general yoke shape with the extremities of its upper ends deflected, as represented at 11, to form trunnions at which it is adapted to

be journaled in operative position. In the construction illustrated, the trunnions 11 are confined in openings 12 in clips 13 bolted to the removable sections of the guides 6, the clips 13 being readily attached to these 60 guides by certain of the screws 14 commonly provided for securing these removable guides to the frame 5 of the machine, the clips 13 being preferably so constructed that the trunnions 11 will extend substantially in vertical line with the male elements 65 of the machine.

The upper and lower portions of the arms 15 are relatively offset, as clearly illustrated in Fig. 1, and are connected by inclined sections 16 forming cams, these offset portions of the guard-proper being so disposed relative to each other that the lower portion of the guard, which includes the lower cross-rail 17, will extend, when in normal position, 75 (Fig. 1) in a vertical plane in the rear of the punch 8 and preferably closely adjacent to the upper surface of the die block 9.

The means for operating the guard-proper 10 to swing it from the position represented in Fig. 1 to the position represented in Fig. 2 upon the descent of the plunger 7, comprise projections 18 provided on plates 19 secured by screws 20 to opposite sides of the plunger 7 in position to engage the upper, cam surfaces, of the deflected portions 16 of the arms 15, as represented in Fig. 1, springs 21 each connected at one end with the frame 5 of the machine and at its opposite end to the adjacent arm 15 of the guard-
85 proper 10, serving to normally hold the guard-proper in retracted position when the plunger is raised (Fig. 1) and return guard-proper to this position after it has been moved to the position illustrated in Fig. 2, 90 upon the plunger returning to raised position.

In the normal position of the machine, namely, that in which the plunger 7 is in raised position, the pins 18 engage at rollers 100 22 thereon preferably with the upper portions of the cam surfaces 16 and the guard is in such position, as represented, as not to interfere with the positioning of the work on the die block 9. As the plunger 7 begins 105 to descend, the pins 18, by moving in a vertical path in engagement with the cam surfaces 16, swing the guard-proper 10, against the action of the springs 21, to the right in Fig. 1, the cross-bar 17 in this movement 110

swinging across the die member 9 from a position in the rear of the punch 8 to a position in front of the latter (Fig. 2). Thus, should the operator, while the plunger 7 is descending, permit his hands to remain in such position that the punch 8 would strike them, they will be engaged by the cross-bar 17 of the guard and pushed out of the path of the punch.

10 To render the guard readily adjustable to machines of different sizes and to varying conditions in a single machine, I prefer to provide it of the construction illustrated, this construction involving the formation of the arms 15 and a portion of the cross-bar 17 of heavy, stiff rods, the sections of rods forming the arms 15, and the up-turned sections of the rods forming a portion of the cross-bar 17, being connected together by coupling blocks 23 with set-screws, as illustrated, for securing these parts in relatively adjusted position. The adjacent ends of the sections of rods which, in part, form the cross-bar 17, fit into the opposite ends of a tube 24 and are adjustable lengthwise therein to reduce or increase, as desired, the width of the guard-proper 10, set-screws 25 screwing into the tube 24 (the only of which set-screws is shown), serving to hold the parts forming the cross-bar, in relatively adjusted positions.

What I claim as new and desire to secure by Letters Patent is:—

1. The combination with the die-plate and the punch-plunger of a punch-press, of a guard therefor comprising a member supported on a relatively stationary part of the press to be swung across the path traversed by said punch and having a cam surface, and means on said plunger adapted to engage said cam surface for swinging said guard across the path traversed by said punch as the latter descends.

2. The combination with the die plate and the punch-plunger of a punch-press, of guard means comprising clips secured to a relatively stationary part of the press, a guard-proper journaled on said clips to be swung across the path traversed by said punch and having a cam surface, and means on said plunger adapted to engage said cam surface for swinging said guard across the path traversed by said punch as the latter descends.

3. The combination with the die plate and the punch-plunger of a punch-press, of guard means comprising angle-shaped clips secured to a relatively stationary part of the press, a guard-proper journaled on said clips to be swung across the path traversed by said punch and having a cam surface, and means on said plunger adapted to engage said cam surface for swinging said guard

across the path traversed by said punch as the latter descends.

4. A guard-proper for the purpose set forth, comprising a yoke-shaped member having its arms, at which it is adapted to be supported to be swung back and forth, formed of sections adjustable lengthwise relative to each other and its cross-bar formed of longitudinally adjustable sections.

5. A guard-proper for the purpose set forth, comprising a yoke-shaped member formed of relatively adjustable sections adapted to permit the arms and cross-bar of said member to be lengthened and shortened to adapt the guard to varying conditions.

6. A guard-proper for the purpose set forth, comprising a yoke-shaped member with its cross-bar formed of a pair of angle-shaped sections and a tube each of said sections fitting at one end in said tube and adjustable lengthwise therein with means for releasably securing them in adjusted position, connectors connected with the upper ends of said angle sections, and sections forming the arms of said yoke secured to said connectors.

7. The combination with the die plate and the punch-plunger of a punch-press, of a guard therefor comprising a yoke-shaped member journaled at its arms on a relatively stationary part of the press and extending at its cross-bar adjacent to the die plate and adapted to be swung back and forth across the latter, said cross-bar being rearwardly offset relative to the journal supports for said yoke member and provided with cam surfaces, a spring operating to normally hold said guard member in a position in which its cross-bar will extend in the rear of the punch carried by said plunger, and projections on said plunger operating upon the descent of said plunger to engage said cam surfaces and swing said yoke member, against the action of said spring, forwardly, and move its cross-bar beneath, and to a position in front of the punch on said plunger.

8. The combination with the die-plate and the punch-plunger of a punch-press, of a guard therefor comprising a member supported on a relatively stationary part of the press, in a position not forward of the center line of the punch-plunger, to be swung across the path traversed by said punch-plunger and having a cam surface, and means on said plunger adapted to engage said cam surface for swinging said guard across the path traversed by said punch as the latter descends.
